CLOTHESPIN

Maud Kandel Kislingbury and Edna Emma
Runge, Alta, Iowa

Application January 9, 1939, Serial No. 249,948

1 Claim. (Cl. 24—84)

The principal object of this invention is to provide a clothespin which may be attached to the clothes line by means independent of its jaw portions.

5 A further object of our invention is to provide a clothespin having resilient serrated jaw elements for securely gripping the clothes or like.

A still further object of this invention is to provide a clothespin which may be left permanently on a clothes line and the clothes clamped thereto on which may be attached to the clothes and then strung on the line.

10 A still further object of our invention is to provide a clothespin that is economical in manufacture, durable and efficient in use.

These and other objects will be apparent to those skilled in the art.

Our invention consists in the construction, arrangement and combination of the various parts 20 of the device, whereby the objects contemplated are attained as hereinafter more fully set forth, pointed out in our claim and illustrated in the accompanying drawing, in which:

Fig. 1 is a side elevational view of our clothespin ready for use.

Fig. 2 is a side elevational view of our clothespin more fully illustrating its construction.

Fig. 3 is an enlarged cross sectional view of the clothespin taken on the line 3—3 of Fig. 1.

30 Fig. 4 is an enlarged perspective view of the rubber jaw inserts used on our clothespin.

Fig. 5 is an enlarged side sectional view of a modified form of structure of our pin showing one of the clips stamped from the metal body 35 of the clothespin.

Fig. 6 is a side view of our clothespin, using the modified form of structure shown in Fig. 5.

There are many types of clothespins now on the market. With all of these types, however, 40 it is necessary to place the clothes on the line and then pin them to the line with the pin. Also the pins must be completely removed from the line each time the clothes are removed. This is very unsatisfactory due to the fact that it 45 is necessary to hold the pins in one hand while at the same time holding the clothes. This procedure increases the work attending the hanging of clothes and similar items on a line. Furthermore, it is easy to drop the pins into the dirt 50 and these clothespins are otherwise extremely unhandy. We have overcome such disadvantages as will be hereinafter more fully set forth.

Referring to the drawing, we have used the numeral 10 to designate one of the channel 55 frame members or jaw elements of our pin hav-

ing integrally formed thereon a handle portion 11 and ears 12 as shown in the drawing.

The numeral 13 designates a similar channel frame member or jaw element having thereon a handle portion 14 and ears 15. The ears 15 are depressed so that they may fit adjacent the inner surfaces of the ears 12 and the two arms are then held in pivotal alignment by a shaft 16 in the usual manner. We have used the numeral 17 to designate a spring coiled about the shaft 16 and having its end portions 17' bearing against the inside of the handles 11 and 14 as shown by dotted lines in Fig. 1 of the drawing. The numerals 18 and 19 indicate two blocks of rubber or other resilient material which are crimped into the channel members 10 and 13 respectively as shown in the drawing. These resilient blocks 18 and 19 have their inner, adjacent faces serrated so as to form a gripping surface as shown. We have used the numeral 20 to designate a spring clip element having one end rigidly secured to the handle portion 11 and its open end extending toward the channel jaw portions of the clothespin. The numeral 21 indicates a similar spring clip member rigidly secured to the handle member 14. I have designated a clothes line or like by the numeral 22. Referring to Fig. 5 of the drawing, it will be noted that a clip 21' may be stamped from and integrally with the handle portion 14', thus reducing the number of parts necessary in the construction of the clothespin.

In practical use our clothespin is extremely versatile. Either of the clips 20 and 21 may be clipped onto the clothes line and the user may then slide the pin to the desired position. The handles 11 and 14 are then pressed together so that the clothes may be clamped between the resilient faces 18 and 19. The pin may be left permanently on the line 22, may be strung on two parallel lines so that the pin is always in a vertical position, or the pins may be clamped onto the clothing or like and then the clothespin clipped onto the line. For instance, the user may attach the goods to the clothes in the house and then it is only necessary to clip either of the clips 20 or 21 onto the line. These clothespins may be utilized in drying film, pictures, art goods, and in fact anywhere a clip may be used. The rubber or like jaw members prevent injury to materials and firmly grip the material being held. Our clothespin aids materially in reducing the work required in hanging up clothes and the like.

Thus it will be seen that we have provided 55

a clothespin that fulfills all of our objects and presents many more obvious advantages. Our clothespin is rugged, may be easily cleansed, is unbreakable and does not snag or injure clothes 5 or the like.

Obviously, our clothespin may be constructed with but one of the clips thereon but for convenience and versatility, we have used two of the clips.

10 Some changes may be made in the construction and arrangement of our improved clothespin without departing from the real spirit and purpose of our invention, and it is our intention to cover by our claim any modified forms of 15 structure or use of mechanical equivalents which may be reasonably included within its scope.

We claim:

In a clothespin, an elongated channel frame member, a handle member integrally formed on

one end of said channel frame member, a second elongated channel frame member, a handle member integrally formed on one end of said second channel frame member, ears integrally formed on each of said channel frame members, a means 5 for pivotally securing the ears on said first and said second mentioned channel frame members to each other, a means for yieldingly holding said channel frame members adjacent each other, serrated resilient block members received by and 10 rigidly secured to the other end of each of said elongated channel frame members; said serration on said resilient block members extending beyond the marginal edges of said elongated channel frame member, and clipping elements 15 stamped and integrally formed from the center portions of each of said handle members.
